UNITED STATES PATENT OFFICE

2,111,084

CIGARETTE STUB HOLDER

Selma Anderson, Tacoma, Wash.

Application February 23, 1937, Serial No. 126,979

2 Claims. (Cl. 131—51)

This invention relates to devices adapted to receive and hold a partially smoked cigarette and has for its objects to provide a device which will automatically hold the cigarette in upright position and also extinguish the fire therein; which will keep the stub clean so that, if desired, it may be relit and smoked; and which is cheap and simple to make and effective in action.

I attain these and other objects by the devices and arrangements illustrated in the accompanying drawing, in which—

Fig. 1 is a side elevation of an ash-tray equipped with my device; Fig. 2 is a cross-section thereof; and Fig. 3 is a view similar to Fig. 2 showing a cigarette stub being held thereby.

Similar numerals of reference refer to similar parts throughout the several views.

It will be understood that my device may be applied to any desired form of support, usually an ash-tray and may be made of any desired materials suitable for the type and style of ash-tray.

Referring to the drawing, it will be seen that the ash-tray 1 is provided with two ears 2 extending vertically therefrom. A pair of parallel rods 3 are mounted in the two said ears 2 and extend across the ash-tray 1. The rods 3 are spaced apart a distance slightly greater than the diameter of a cigarette. A pair of tubes 4 are loosely mounted on the said rods 3, and are free to swing laterally thereon.

When no cigarette is being held by my device the axis of the said tubes 4 is each vertically below that of the supporting rods 3 (Fig. 2) and the free space between the tubes 4 is less than the diameter of a cigarette.

When a lighted cigarette stub is pushed down between the tubes 4 it is thereby pinched to

extinguish the fire and it forces the tubes 4 laterally so that the axes thereof are no longer vertically below the axes of the respective rods 3 but are swung laterally outward. In this position (Fig. 3) the weight of the tubes 4 apply 5 a gripping action on the cigarette between them and firmly hold it in such upright position.

It is, of course, understood that the invention illustrated and described herein is in the preferred form but that many variations may be 10 made in the details thereof without departing from the spirit of my invention as outlined in the appended claims, for instance, the rods 3 may not extend entirely across the tray but may be in the form of pins extending inward from the 15 ears 2 and thus holding the tubes thereon. The tubes may be made of metal, glass, or any other suitable material.

The words and terms in the description and claims are chosen for convenience but are intended to be as generic in their meaning as the art will permit.

Having, therefore, described my invention, what I claim and desire to secure by Letters Patent, is:—

1. A cigarette stub holder, comprising a pair of complementary supported ears; a pair of parallel rods supported by said ears; and a pair of tubes loosely mounted on said rods, whereby said tubes are adapted to be thrust laterally by a cigarette placed between them and thereby to apply a holding force thereto.

2. A cigarette stub holder, comprising a pair of complementary supporting ears; a pair of parallel tubes; and means on said ears and loosely 35 engaging the inside of said tubes, whereby each said tube is loosely supported by both said ears.

SELMA ANDERSON.
